UNITED STATES PATENT OFFICE.

MICHAEL H. SULLIVAN, OF POUGHKEEPSIE, NEW YORK, ASSIGNOR TO JOHN LAWRENCE MURPHY, OF CHELSEA, MASSACHUSETTS.

ROTARY COMPOUND EXPLOSIVE-ENGINE.

1,006,417.

Specification of Letters Patent.

Patented Oct. 17, 1911.

Application filed August 16, 1905, Serial No. 274,441. Renewed March 6, 1908. Serial No. 419,569.

To all whom it may concern:

Be it known that I, MICHAEL H. SULLIVAN, a citizen of the United States, residing at Poughkeepsie, in the county of Dutchess 5 and State of New York, have invented new and useful Improvements in Rotary Compound Explosive-Engines, of which the following is a specification.

My invention is an improved rotary compound explosive engine, and its primary object is to provide an engine in which both the pressure energy and the velocity or impact energy of gases may be utilized to the fullest extent, this object being attained by 10 providing a rotary motor having rotary pistons and means for generating and exploding an explosive mixture which is directed against the pistons to utilize the explosive or pressure energy of the gases, and by connecting to the motor shaft so as to turn therewith, impact vanes or buckets against which the gases discharged from the rotary motor are directed so as to utilize the impact or velocity energy of said gases and 15 thus compound the action of the engine.

A further object is to provide an improved form of engine of this class having a revoluble wheel provided with pistons and with vanes or buckets, means to apply fluid under 20 high pressure to the said pistons, to rotate said revoluble wheel, and an accumulator into which the exhaust discharges and in which the same expands, said accumulator supplying fluid for operation against the 25 vanes or buckets and compounding the action of the engine.

In the accompanying drawings, Figure 1 is a top plan view of an engine embodying my improvements; Fig. 2 is an elevation 40 of the same, the shaft being shown in section on the plane indicated by the line $a-a$ of Fig. 1; Fig. 3 is a detail perspective view from the inner side, showing one of the casing sections; Fig. 4 is a similar view, 45 showing the other casing section; Fig. 5 is a vertical transverse sectional view, taken on the plane indicated by the line $b-b$ of Fig. 1; Fig. 6 is a detail elevation of the revoluble element; Fig. 7 is a detail elevation of 50 one of the pistons of the revoluble element; Fig. 8 is a sectional view, taken on the plane indicated by the line $c-c$ of Fig. 1, and intersecting the carbureter or vaporizer; Fig. 9 is a detail sectional view of one of 55 the combustion chambers, illustrating its re-

lation to one of the piston chambers of the engine casing and also showing the valve which regulates the admission of the charge to the combustion chamber and controls communication between the combustion chamber and the piston chamber, to permit the charge when exploded to expend its force in the piston chamber; Fig. 10 is a vertical longitudinal central sectional view of my improved engine, and Fig. 11 is a detail 60 sectional view of one of the packing rings of the piston-carrying wheel and its connections.

The casing 1 of my improved engine is composed of two sections 2, 3. The section 70 2 has the portion 4 which is cylindrical in form and of enlarged diameter, and the portion 5, which is also cylindrical in form, is of smaller diameter than the portion 4, and is on one side thereof. The enlarged portion 4 forms a cylindrical wheel chamber 6 for the revolving piston-carrying wheel 7. The section 3 comprises a flat, circular inner portion 8 which is bolted to one side of the section 2 by bolts 9, said section 2 having 80 a peripheral flange 10 through which the said bolts pass. The said section 3 also has a portion 11, of cylindrical form, which corresponds in size with the portion 5 of the casing section 2. The said casing is supported by legs 12.

The wheel 7 is mounted on a shaft 13 which extends concentrically through the casing, and the ends of which shaft are journaled in thrust bearings 14 which are 90 provided with adjusting screws 15, the inner ends of which are stepped in recesses in the ends of said shaft. The said screws prevent casual endwise movement of the shaft and corresponding transverse movement of the 95 wheel 7, and also enable the shaft and wheel to be adjusted to prevent undue friction between either side of the wheel and either side of the casing.

The wheel 7 is provided with a plurality 100 of radially-disposed slots 16, two being the preferred number, as here shown, and arranged diametrically opposite each other. The said slots extend from within a suitable distance of the center of the wheel to within 105 a suitable distance from the periphery thereof, and within each of said slots is placed a piston 17, which is slidable therein transversely with reference to the wheel. In the sides of the said slots are antifriction rollers 110

18 which bear against opposite sides of the pistons and prevent undue friction thereof. The ends of the pistons bear against the inner surfaces of the irregular walls of the 5 casing sections. The irregular surfaces of the walls of each section are arranged diagonally and in alternation with each other, so that when the sections are united, the inner points 19 of one section will be arranged 10 opposite the extreme outer points 20 of the opposite section, and as the edges 19 of each section abut against the wheel 7, it will be seen that I provide a series of four separate and distinct chambers 21 in which the pistons 15 operate.

In the inner face of the periphery of the enlarged portion 4 of the casing section 2 is a cam groove 22 which extends obliquely across the same and annularly within the 20 said casing section, and which is parallel at all points with the walls in the ends of the casing section. Each piston 17 has a pin 23 projecting from its outer side, at its center, and on the outer end of which is 25 mounted an anti-friction roller 24 which travels in the cam groove 22 and coacts with said cam groove to impart reciprocating movement to the piston. The peripheral portion of the wheel 7 is provided with 30 transverse slots 25 in which operate anti-friction rollers 26 which are journaled on the said pins 23. The wheel 7 is provided on opposite sides, at suitable distances from its center and periphery with concentrically-disposed packing rings 27 which are 35 recessed therein and each of which is provided with a plurality of inwardly extending studs 28 which enter the transverse openings in the wheel, have their inner ends hollowed, and are provided with coil springs 40 which act to keep the said packing rings in contact with the sides of the casing. It will be understood that said packing rings are carried by and revolve with the said 45 wheel. The abutments formed by the irregular end walls of the casing sections are provided at their apexes with packing plates 30 which are held by springs 31 in frictional engagement with the sides of the wheel. 50 One of the piston chambers 21 in each side of the piston casing has an inlet channel 31^a and an exhaust port 32, and the casing has an accumulating or expanding chamber 33 formed therein, here shown as extending 55 nearly entirely around the same and terminating in a discharge port 34, in which is placed a nozzle 35 that is disposed obliquely with reference to and discharges correspondingly against one side of the wheel 7, near 60 the periphery thereof. The peripheral portion of the wheel 7 is provided with obliquely-disposed transverse chambers 36 which form impact vanes, against which strike the exhaust products discharged from 65 the piston chambers into the accumulating

or expanding chamber 33 and discharged from said chamber 33 so that the exhaust gases or products are utilized in rotating the piston-carrying wheel, thereby compounding the action of the engine, as will be understood. The exhaust is indicated at 73. One piston chamber in each section of the casing is provided with a cold air intake port 37 and an air discharge port 38. The shaft 13 drives an air compressor 39 which compresses air in a tank or reservoir 40.

The compressed air tank is connected by pipes 41 with vaporizers 42, each of which comprises an inner, vaporizing chamber 43, and an outer, heating chamber 44, which extends around but does not communicate with the vaporizing chamber. In the vaporizing chamber is a cylindrical valve chamber 45 in which operates an oil feed valve 46, which is cylindrical in form and has an annular recess 47 that forms an oil duct. A port 48 connects the valve chamber with the vaporizing chamber, and there is an oil-supply pipe 74 that leads to said valve chamber. A spring 50 normally maintains the valve 46 in position to cut off communication between the oil-supply pipe and the vaporizing chamber. Said valve has a rod 51 provided with a tappet roller 52 which bears against a cam 53 on the shaft, said cam acting once at each rotation of the shaft to move the valve against the tension of the spring, so that the oil duct registers with the oil supply pipe and the port 48, and hence causes a charge of oil to be fed to the vaporizing chamber. The pipe 41 communicates with the vaporizing chamber, so that the latter is supplied with compressed air, heated by radiation from the heating chamber 44, and hence the oil serves to carburet the air, the oil and air forming a highly combustible and explosive vapor or gas, as will be understood. Each section of the casing 1 has on its outer side a combustion chamber 54 which communicates with one of the ports 31^a and also communicates with the vaporizing chamber of one of the vaporizers by a duct 55. Said duct is normally closed by a valve 56. A spring-pressed valve 57 normally closes the port 31^a. The said valves are operated by cams 58 on the shaft, said cams being so timed as to first open and close the valve 56, to charge the combustion chamber, and to then open the valve 57 at the instant of the ignition and explosion of the charge, so that the force of the exploded charge will pass into one of the chambers 21, behind one of the pistons, to revolve the piston-carrying wheel. The respective combustion chambers with their valves, on opposite sides of the casing, are so located that the charges therein are alternately exploded and their force directed into chambers 21 on opposite sides of the wheel, thereby causing the latter to run steadily and evenly.

It will be understood that the force of the exploded charges acts on the pistons in only one of the chambers 21 on each side of the wheel. The other of such chambers on each side of the wheel has its port 37 provided with a cold air intake pipe 59, and its port 38 connected by a pipe 60 to the outer, heating chamber 44 of one of the vaporizers, said chamber being provided also with a 10 discharge pipe 61 which may lead either to the outer air or to a suitable gas producer or carbureter, as may be desired. It will be understood that at each rotation of the wheel, cold air will be sucked into one of 15 the chambers 21 on each side thereof, which will prevent overheating of the engine, the air will be highly heated, and will be driven through the outer, heating chambers of the vaporizers before being discharged, and 20 hence the heated air will serve to keep the vaporizers heated to the degree required to vaporize the carbureted air fed to the vaporizing chambers thereof from the compressed air reservoir. Each combustion chamber 25 has a spark or igniter 62, here indicated as an electric spark, and said sparkers are operated by cams 63 on the shaft.

From the compressed air tank or reservoir 40 leads a pipe 64 which communicates 30 with the chambers 21 in which the pistons operate through branch pipes 66. A valve 67 controls the said pipes, and when the engine is to be started, said valve is opened, thereby admitting compressed air directly 35 into the piston chambers and utilizing the compressed air to start the engine. Said valve is then closed, and the engine continues to operate, as before described.

The air compressor 39 is similar in construction to the casing 1, and the piston-carrying wheel therein, the wheel in the air compressor being operated directly by the engine shaft. The said air compressor has an air inlet valve 68. The compressed air 45 tank or reservoir 40 communicates with a cylinder 69, in which is a piston 70 which is moved in one direction by a spring 71, and, upon an excess of pressure in the said tank or reservoir 40, is moved in the opposite direction by the said excess pressure. A link 50 72 is here shown as connecting the said piston to the lever of the valve 68, so that on an excess of pressure of air in the tank 40, the piston 70 will be operated to close or 55 partly close the valve 68, as the case may be, to put the air compressor either entirely or partly out of action, and hence diminish the pressure of the explosive charges fed to the piston chambers of the engine from the 60 compressed air tank and correspondingly reduce the efficiency of such charges in driving the engine, thereby preventing the engine from running at too high a rate of speed.

65 From the foregoing, it will be seen that in

practicing my invention, I utilize a rotary motor having rotary pistons against which exploded gases are directed so as to permit of a high velocity being obtained, I associate with such motor explosive chambers 70 and means for generating and exploding the charges and directing them against the rotary high pressure pistons, I arrange impact vanes or buckets to rotate with the motor shaft, and I provide an accumulator 75 which receives the gases from the rotary explosive motor and directs them against the impact vanes or buckets to compound the action of the engine. By utilizing rotary high pressure pistons, a very high speed can 80 be developed and in associating with such rotary pistons, the impact or turbine vanes to receive the velocity or impact energy in the gases after they leave the high pressure piston chambers, both the pressure energy 85 and the velocity energy of the gases are utilized to the fullest extent and, consequently, more of the original heat in the gases is converted into useful mechanical work than in other engines in use at the 90 present time.

Having thus described my invention, what I claim as new and desire to secure by Letters-Patent is:

1. An engine of the class described, comprising a wheel casing provided at its sides with high pressure chambers, a wheel mounted for rotation in said casing and having pistons to operate in said chambers, said wheel being provided with peripheral impact vanes or buckets, a shaft driven by said wheel, an air compressing element operated by said shaft, means for storing the product of said compressing element, means to admit air to the engine from said storing 95 means to start the engine, means for generating high pressure fluid to act upon said pistons, and an accumulator into which the chambers exhaust, said accumulator having a discharge portion entered tangentially 100 into the casing in position to inject the exhaust fluid against the vanes or buckets.

2. An engine of the class described having a casing provided with a wheel chamber, high pressure piston chambers on opposite 105 sides thereof, an accumulator into which the exhaust from the high pressure chambers discharges, said accumulator having a discharge port leading to the outer portion of the wheel chamber, a revoluble wheel in the 110 wheel chamber, movable pistons carried thereby to operate in the high pressure chambers, air compressor means driven by the wheel, means engaged by the discharge 115 from the accumulator to assist in turning said wheel, means to generate high pressure fluid to act upon said pistons, a storage tank connected to the air compressor, and means for admitting air from the storage tank to 120 the engine to start the same.

3. An engine of the class described comprising a wheel casing having its side walls recessed to form high pressure chambers, a wheel mounted for rotation in said casing and having pistons to operate in said chambers, said wheel being provided with impact vanes or buckets, air compressor means driven by said wheel, a tank connected to the compressor, means to admit the air from the tank to the engine for primary starting purposes, means for supplying fluid under pressure to the chambers to act on said pistons, and an accumulator extended marginally around the casing and into which the chambers exhaust, said accumulator having a discharge nozzle entered tangentially into the casing in position to inject the exhaust fluid against the vanes or buckets for compounding the action of the engine. 70
4. An engine of the class described having a casing provided with a wheel chamber divided into a high pressure compartment and a secondary compartment, a revolute wheel in said wheel chamber having movable pistons carried thereby operating in the high pressure compartment, said wheel being further provided with driving devices operated in the secondary compartment of the wheel chamber by the exhaust from the high pressure piston compartment, an air compressor driven by said pistons, means admitting the air from said compressor to said engine for initial starting purposes, and means for generating high pressure products of combustion for said pistons. 95
5. An engine of the class described having a casing, a revolute wheel therein having movable pistons carried thereby and further provided with peripheral vanes or buckets, said casing having high pressure chambers in which the pistons operate, a chamber in which the peripheral vanes or buckets operate, concentrically disposed packing rings on the sides of the wheel, said packing rings being carried by and revolving with the wheel and bearing against the end wall of the casing one at a point between the pistons and said chamber, and the other at a point between the pistons and the center of the wheel, an air compressor driven by the wheel, a tank connected to the air compressor, means admitting the air from the tank to the engine to act upon said pistons, and means for generating high pressure fluid to act upon said pistons. 100
6. An engine of the class described, comprising a wheel casing provided with high pressure chambers, a shaft journaled for rotation in said casing, a wheel arranged in the casing for rotation with said shaft and having movable pistons to operate in said chambers, said wheel being provided with peripheral vanes or buckets, an air compressor driven by said wheel, a reservoir connected to said compressor, means for controlling the passage of air from the reservoir to the engine for initial starting purposes, means for generating high pressure fluid to act upon the pistons, and an accumulator into which the chambers exhaust, said accumulator having a discharge portion entered into the casing in position to inject the exhaust against the vanes or buckets for compounding the action of the engine. 115
7. An engine of the class described having a casing provided with a wheel chamber, a revolute wheel in the wheel chamber, high pressure piston chambers on opposite sides of said wheel chamber, an accumulator into which the exhaust from the high pressure chambers discharges, rotary vanes positioned to be engaged by the discharge from the accumulator, pistons in the high pressure chambers carried by the wheel, means for generating power fluid to initially start the engine, and explosion chambers for generating high pressure fluid for use in said piston chambers. 120
8. A rotary compound explosive engine comprising a rotatably mounted shaft, a wheel carried by said shaft and carrying rotary pistons, a casing for the wheel and provided on opposite sides of the latter with high pressure chambers in which said pistons operate, combustion chambers in communication with the high pressure piston chambers, means for generating explosive charges and admitting them to said combustion chambers, means for exploding charges in said combustion chambers and directing the exploded gases against the high pressure pistons, an accumulator to receive the gases discharged from the high pressure chambers, an annular series of impact vanes or buckets connected to said shaft to rotate therewith, means for directing the gases in said accumulator against said vanes or buckets for compounding the action of the engine, air compressor means driven from said shaft, a tank connected to the compressor, and means for admitting air from the tank to the engine for primary starting purposes. 125
9. A rotary compound explosive engine comprising a rotatably mounted shaft, a wheel upon the shaft and carrying rotary pistons, a casing for the wheel providing high pressure chambers on opposite sides of the latter in which said pistons operate, an annular series of impact vanes or buckets movable with said shaft, combustion chambers communicating with the high pressure piston chambers, igniting devices for said combustion chambers and actuated from said shaft, an air compressor actuated from said shaft, an air tank connected to the air compressor, means connected to said tank and to said combustion chambers for generating explosive charges, including a valve actuated from said shaft, means actuated from said shaft for admitting the explosive charges. 130

into said combustion chambers and means actuated from said shaft for admitting exploded gases from the combustion chambers to said high pressure piston chambers, an accumulator to receive the gases discharged from the high pressure piston chambers, means for directing the gases in said accumulator against said vanes or buckets to compound the action of the engine, means to admit air from said tank to the engine for pri-

mary starting purposes, and means controlled by the pressure in said tank for controlling the air compressor.

In testimony whereof I have signed my name to this specification in the presence of 15 two subscribing witnesses.

MICHAEL H. SULLIVAN.
